WORK SUPPORT

Ernest L. Butler, Lynn, Mass., assignor to United Shoe Machinery Corporation, Borough of Flemington, N. J., a corporation of New Jersey

Application May 18, 1940, Serial No. 335,974

9 Claims. (Cl. 12—123)

This invention relates to shoe rests and is herein illustrated in its application to toe rests intended for use in lasting machines of the type illustrated, for example, in United States Letters Patent No. 1,018,477, granted February 27, 1912, on an application of Matthias Brock.

Machines of the type illustrated in the Brock patent are provided with toe lasting wipers which in the course of their operation have equal movements toward each other, and in order for the wipers to act uniformly on opposite sides of the shoe, the toe of the shoe must be located centrally with relation to the wipers.

It is an object of the present invention to provide a shoe rest which is adapted to locate a shoe centrally relatively to toe wipers or other operating means. With this object in view, the invention in one aspect thereof provides a toe rest comprising a plurality of members arranged to engage opposite side portions of a shoe in the machine, said members being adjustable toward and from each other to accommodate different widths of shoes, and adjustable as a unit widthwise of the shoe. In order that the illustrated shoe rest may conveniently be arranged to operate on both right and left shoes of a given size and style, the illustrated machine is provided with a support for the shoe rest, and the shoe rest and its support, in accordance with a further feature of the invention, are so constructed and arranged that the shoe rest may be located and held in any one of a plurality of predetermined positions relatively to a shoe in the machine. As herein illustrated, the shoe rest is provided with a stem having opposite longitudinal grooves which cooperate with a locating member in a stem-supporting post to locate the shoe rest in positions of 180° displacement about the axis of the stem.

While the invention is herein illustrated in its application to toe rests for use in lasting machines, it is to be understood that the invention is not limited in scope to toe rests or to shoe rests for use in lasting machines but is applicable to shoe rests for use in other types of shoe machines and to shoe rests which operate at portions other than the toe end of the shoe.

These and other features of the invention will now be described with reference to the accompanying drawing and pointed out in the appended claims.

In the drawing:

Fig. 1 is a plan view illustrating a portion of the toe head of a bed-lasting machine having the toe rest of the present invention incorpo-

rated therein, the toe portion of a shoe in the machine being indicated by broken lines;

Fig. 2 is an enlarged view in front elevation of the toe rest, partly in section, the central portion of the stem of the toe rest being broken away;

Fig. 3 is an enlarged view of one side of the head of the toe rest; and

Fig. 4 is a plan view, partly in section, showing the stem of the toe rest in its supporting post.

In Fig. 1 a toe rest embodying the features of the present invention is illustrated in conjunction with the toe head of a lasting machine of the type illustrated in the patent to Brock above referred to. This machine is provided with toe wipers 10 which are operated by longitudinal movement of a sliding shaft 12. Upon operation of the shaft 12, the toe wipers advance longitudinally of the toe portion of a shoe in the machine, and as they advance, they close upon the shoe by pivotal movement about a point which coincides with the adjacent ends of their wiping edges. The path of movement of the wipers is fixed and unvariable and, consequently, it is desirable that the toe portion of the shoe be centered widthwise thereof relatively to the wipers in order that the wipers may operate uniformly on opposite side portions of the shoe upper.

For centering the toe portion of the shoe relatively to the wipers, the illustrated toe rest is provided with upper-engaging members or pads 14 which are preferably made of rubber or other resilient material and arranged to engage opposite side portions of the toe end of a shoe in the machine. The pads 14 are mounted on ball-ended studs 16 (Fig. 2) which swivel in upward extensions 18 of slides 20 which are mounted in slideways in a crosshead 22 at the upper end of a stem 24 mounted in a support herein illustrated as a hollow post 26 (Fig. 4) extending upwardly from the bed of the machine. The swiveling movement of the studs 16 is limited by pins 27 extending from the studs into round openings in the extensions 18 (Fig. 2). The crosshead 22 extends widthwise of the shoe and is held against turning movement by a spline 28 which enters a longitudinal groove 30 in the stem 24. The pads 14 are adjustable toward and from each other to accommodate different widths of shoes by turning a right and left threaded screw 32, the opposite end portions of which are threaded respectively in the lower portions of the slides 20, the central portion of the screw being provided

with a head or knurled thumb-wheel 34 by which the screw is turned. The screw 32 is held in adjusted position by a spring-pressed plug 40 mounted in a bore in one of the slides 20, which bore communicates with the tapped hole in which the screw 32 operates. The pad assembly including the slides 20 and screw 32 is adjustable as a unit widthwise of the shoe to center the toe portion of the shoe relatively to the toe wipers 10. After so adjusting the toe pad assembly, the assembly is secured in adjusted position by screws 36 mounted in the crosshead 22 and arranged to engage opposite sides of the wheel 34. If desired, the screws 36 may be employed to effect the adjustment of the pad assembly as a unit widthwise of the shoe. It will be understood that in so employing the screws 36, they operate alternatively against the wheel 34 as thrust members to move the slides 20 through their sideways in the crosshead 22. After so adjusting the assembly, if one of the screws 36 is spaced from the wheel 34, said screw is brought into engagement with the wheel to hold the assembly in adjusted position. The adjustment of the screws 36 is maintained by compression springs 38 which surround said screws and act against their heads. It will be understood that the pads 14 may be adjusted toward and from each other by turning the right and left threaded screw 32 without disturbing the adjustment of the pad assembly as a unit maintained by the screws 36. In arranging for lasting right-foot shoes, for example, after having previously operated on left-foot shoes of the same size and style, the toe rest is merely drawn upwardly out of the post 26, then turned 180°, and replaced in the post 26. It will be seen from Fig. 4 that the stem 24 of the toe rest is provided with two longitudinal grooves on opposite sides of the stem which receive alternatively the spline 28 which holds the stem against turning movement.

Having thus described my invention, what I claim as new and desire to secure by Letters Patent of the United States is:

1. In a shoe machine, the combination with means for operating on a shoe in the machine, of a toe rest comprising members arranged to engage opposite side portions of the shoe, said members being adjustable toward and from each other to accommodate different widths of shoes and adjustable as a unit widthwise of the shoe.

2. In a shoe machine, the combination with means for operating on a shoe in the machine, of a shoe rest comprising members constructed and arranged to engage opposite side portions of the shoe, means for adjusting said members toward and from each other to accommodate different widths of shoes, and means for adjusting said members as a unit widthwise of the shoe.

3. In a shoe machine, the combination with means for operating at side portions of a shoe in the machine, of a shoe rest comprising members constructed and arranged to engage opposite side portions of the shoe, means for adjusting said members toward and from each other to accommodate different widths of shoes, and a screw for adjusting said members as a unit widthwise of the shoe.

4. In a shoe machine, the combination with means for operating at opposite side portions of a shoe in the machine, of a shoe rest comprising members constructed and arranged to engage opposite side portions of the shoe, means for adjusting said members as a unit widthwise of the shoe, and means operable to adjust said members toward and from each other without disturbing the first-mentioned adjustment.

5. In a shoe machine, the combination with means for operating on a shoe in the machine, of a shoe rest comprising members constructed and arranged to engage opposite side portions of the shoe, said members being adjustable as a unit widthwise of the shoe and reversible to support alternatively left and right shoes.

6. In a shoe machine, the combination with means for operating at opposite side portions of a shoe in the machine, of a shoe rest comprising members constructed and arranged to engage opposite side portions of the shoe, slides on which said members are mounted, a headed stem constructed and arranged to receive said slides, means for effecting equal and opposite adjusting movements of said slides, and means for locating said members as a unit widthwise of the shoe.

7. In a shoe machine, the combination with means for operating at opposite side portions of a shoe in the machine, of a shoe rest comprising members constructed and arranged to engage opposite side portions of the shoe, slides on which said members are mounted, a headed stem constructed and arranged to receive said slides, means for effecting equal and opposite adjusting movements of said slides, means for locating said members as a unit widthwise of the shoe, a support constructed and arranged to receive the stem, and locating means constructed and arranged to operate alternatively at different positions on the stem.

8. In a shoe machine, the combination with means for operating on a shoe in the machine, of a shoe rest comprising members constructed and arranged to engage opposite side portions of the shoe, slides on which said members are mounted, a head constructed and arranged to receive said slides, a right and left threaded screw for adjusting said members toward and from each other, said screw having a head between its ends for turning it, and thrust members constructed and arranged to act on opposite sides of the last-mentioned head to adjust said members as a unit widthwise of the shoe.

9. In a shoe machine, the combination with means for operating on a shoe in the machine, of a shoe rest comprising members constructed and arranged to engage opposite side portions of the shoe, slides on which said members are mounted, a head constructed and arranged to receive said slides, a right and left threaded screw for adjusting said members toward and from each other, said screw having a head between its ends for turning it, and thrust screws constructed and arranged to act on opposite sides of the last-mentioned head to adjust said members as a unit widthwise of the shoe and to hold them in adjusted position.

ERNEST L. BUTLER.
